UNITED STATES PATENT OFFICE.

THEODORE BIRKENMAIER, WALTER A. HEINRICH, AND JOHN B. TRECOTT, OF ST. LOUIS, MISSOURI, ASSIGNEES, BY MESNE ASSIGNMENTS, TO W. N. MATTHEWS CORPORATION, OF ST. LOUIS, MISSOURI, A CORPORATION OF MISSOURI.

METHOD OF AND APPARATUS FOR APPLYING COATINGS.

Application filed August 19, 1921. Serial No. 493,708.

This invention relates to new and useful improvements in methods of and apparatus for applying coatings, such as paint or other liquids, paste, powder, and the like, the objects being to provide a simple and easily manipulative apparatus whereby the material constituting the coating, and which is ejected under pressure, may be diverted by a so-called target forming attachment whereby the column of coating may be diverted upwardly, downwardly, to the right, or to the left, by applying a jet or blast of gaseous fluid, under pressure, such as air, to the center of the column of coating material being ejected to form a crescentic or semilunar target; or by applying oppositely directed and converging jets or blasts of gaseous fluid, such as air, under pressure to the edge of the column of ejected material and to different sides of the axial center thereof, to produce a wide fanlike or ribbon formation of material to the surface being coated; or by applying oppositely directed and converging jets or blasts of gaseous fluid, such as compressed air, to opposite sides of the center of the ejected column of coating to form a narrow fanlike or elliptical form of target; or by further adjustment of said target forming attachment, to eject a column of coating which will form a circular target. Heretofore it has been proposed to eject coating material under pressure and to change its column formation into a more or less flattened elliptically shaped target by directing diametrically opposite and converging jets thereagainst at points whose greatest intensity is coincident with the axial center of the column. These fan-forming jets are directed from opposite sides against the axial or center line of the column usually at the same pressure as is used to eject the material and will produce a target of considerably flattened elliptical shape, but on account of the intensity of the opposing jets at the center of the column, a so-called "fish-tail" target will sometimes result, i. e., a target where the material is lightly and very thinly applied at the center and more heavily applied at the sides. It has also been proposed to regulate the pressure of the converging lateral jets and while this may obviate, to a certain extent, the "fish-tail" ef-

fect, it at the same time lessens the major axis of the target by producing a "fatter" ellipse, i. e., one more nearly round. 55

It is the purpose of our invention to produce circular, unilateral and bilateral targets by the employment of the same apparatus. In the production of the unilateral target, a blast or jet of air under pressure is directed at an angle, preferably, less than 90° against the column of material ejected under pressure and preferably at a point where the line of greatest intensity of the jet or blast intersects the axial line of the column so as to divert or bend the column to one side, thus producing a crescentic or semilunar target. As the issuing coating material is preferably ejected so as to produce a target of circular form, it is clear that a 60 blast or jet of air whose greatest intensity is at its center, directed against the axial line of the column will more effectively divert the column in the production of a semi-elliptic or crescentic target, because it has, when so directed at the axial line, a greater mass of material to move. In other words, the unilateral target is produced by the use of a single lateral blast by utilizing in part 65 the same laws of operation which obtain with respect to the sometimes objectionable "fish-tail" target. Realizing this fundamental principle, and utilizing it to the best advantage in the production of a unilateral target, and a narrow elliptical target, we 70 employ a different law of operation in the production of a wide ribbonlike target. 75

This different law of operation may be stated to consist in the diverting of the edges only of the columnlike stream of ejected flowing material. These jets or blasts of air are thus eccentrically disposed to the column, and their line or lines of greatest intensity located near the centers thereof, strike the column of material to the side of its axial line. Thus, the diverting and oppositely directed blasts have no common point of intersection (except possibly at their edges) and are free to pass each other so as to uninterruptedly carry with them portions of the material in the formation of the wide ribbonlike target. In this manner, the particles of coating material at or near the center of the column are not disturbed, and, 80 85 90 95 100

hence, the formation of a "fish-tail" target is avoided. Furthermore, the major axis of the target is considerably increased.

To illustrate: A spray gun equipped with a target-forming attachment whose lateral jets or blasts of air are directed to the axial line of the pressure ejected material, and placed about eighteen inches from the surface to be coated, will produce a narrow elliptical target whose major axis is from eight to ten inches; whereas where the jets of air are tangentially disposed and pass each other as contemplated by us, a spray gun operating under the same conditions at the same distance from the surface to be coated, would produce a wide ribbonlike target whose major axis is from twenty-five to thirty inches and whose center is as solid and as evenly coated as its ends.

20 In the accompanying drawings:

Figure 1 is a side elevational view of our spray gun employed in carrying out our method;

25 Figure 2 is a front elevational view thereof showing the target forming attachment;

Figure 3 is a front elevational view thereof, with the target forming attachment removed therefrom;

30 Figure 4 is a vertical sectional view through the nozzle end of the gun;

Figure 5 is a similar view showing the parts in a changed position;

Figure 6 is a detail view of the spider plug in the discharge end of the nipple;

35 Figure 7 is a sectional view of a modified form of target forming attachment;

Figure 8 is a front elevational view of the form shown in Figure 7;

Figure 9 is a detail front elevational view 40 of the valve seat;

Figure 10 is an enlarged view of the paint controlling valve stem showing the same in a position to permit the passage of a large supply of paint into the air passage;

45 Figure 11 is a similar view showing the position of the parts in admitting a small amount of paint to the air passage;

Figure 12 is a similar view showing the position of the valve wherein the paint passages are closed and back air pressure is permitted to flow through the paint passages;

50 Figure 13 is a detail side elevational view of the paint controlling valve;

Figures 14 to 25, inclusive, are diagrammatic views showing different positions of the target forming attachments on the form of spray gun illustrated in Figures 1 to 6.

55 Figures 26 to 37, inclusive, are diagrammatic views showing the different positions of the target forming attachment on the form of spray gun illustrated in Figures 7 to 13.

In the drawings, referring particularly to Figures 1 to 6, 1 indicates a casting resembling a pistol in general shape, on the han-

dle of which is a nipple 2 for supplying air under pressure to the gun. 3 is the nipple to which a paint supply pipe, not shown, may be connected. These air and paint supply pipes are preferably of tubular rubber.

70 4 is a trigger for controlling the stems 5 and 6 of the air and paint valves, respectively. The parts above referred to may all be the same as those disclosed in the Heinrich Patent No. 1,382,640.

The compressed air passes through the centrally arranged conduit of the barrel in the end of which is threaded a nipple 7 having a hexagonal head for well understood purposes.

75 The protruding end of this nipple is preferably cylindrical in form and its orifice contains a spider-like plug 8. Plug 8 is provided with a central opening for forming a constricted orifice for the jet of air which ejects

80 the column of material from the gun. Around the edges of this plug are a series of

85 grooves or recesses 8a, the purpose of which is to permit small quantities of air to pass

therethrough, thereby keeping the wall of the air conduit behind the plug comparatively clean and free from dirt and dust.

9 indicates a nozzle member threaded

onto the end of the barrel of the gun and forming a material supply chamber into

which material from a source of supply enters through the lateral conduit 9a.

90 10 indicates a material-controlling valve

in the form of a hollow stem threaded into

the forward end of nozzle 9, the outer end

of said threaded stem being provided with

100 a knurled head by which the valve may be

positioned and adjusted. This valve stem is

provided with a differential bore forming a

shoulder 10b and when the valve is screwed

105 inwardly, this shoulder is seated against the

end of nipple 7, as shown in Figure 4, thereby

preventing paint, or other material, from

passing out through the stem; but when said

valve is adjusted outwardly, as shown in

110 Figure 5, the paint or other material enters

in the rear end of the larger bore of the

valve stem and passes forwardly in the

space therebetween and the nipple 7 until

it is within the smaller bore of the valve

stem, at which time it is ejected in the form

115 of an atomized tapering column which will

produce a circular target on the surface

being painted, and the size and surface cov-

erage depends largely upon the distance the

gun is held from the surface being covered,

the pressure of air used, the viscosity of the

paint and the pressure at which the paint

is supplied to the nozzle chamber. It is ob-

vious that when the valve member 10 is seat-

ed against the end of the nipple, paint will

not be permitted to pass through the re-

stricted orifice of the valve member; but by

adjusting this valve member away from the

end of the air nipple, the quantity of paint

120 ejected from the gun may be regulated and

130

controlled. The further the shoulder 10^b is moved away from the end of the nipple, the less friction there will be offered to the paint and consequently the greater the quantity of paint ejected.

11 indicates a ring valve seat forming with the barrel an annular air space or chamber which is in communication with the compressed air conduit of the gun. There are a series of openings or ports through this valve seat indicated at 11^b. There may be any number of these openings spaced and arranged according to the wishes of the designer, but we have shown in one form of our invention, eight ports or openings grouped together as four pairs, slightly displaced with respect to the vertical and horizontal axial planes of the barrel of the gun.

12 indicates the target-forming attachment having a base ring 12^x provided with a valve seat for co-operating with the valve seat ring 11. This target-forming attachment 12 is provided in the present form of our invention with air ports A, B and C formed in parallel extensions or arms 12^a, and passing through the crater-like face of an outer portion of the base head ring.

Referring to Figure 2, it will be noted that the ports A and B are diametrically opposed to each other and emit blasts or jets of air on each side of the column of ejected material, and by reference to Figure 4 it will be seen that these jets pass each other at approximately the same point with respect to the axial line of the column of material. Port C is indicated by the arrow in Figure 2, and emits a blast of air which is directed against the axial line of the column of material.

The valve seat ring 11 is preferably provided with an arrow or positioning mark, and the base ring 12^x of the target forming attachment is likewise provided with positioning marks, each of the latter having an initial, indicating the character or shape of the target produced when the target forming attachment is rotatably adjusted to locate the proper indicia opposite the positioning mark on the valve ring seat. For instance, the base ring may be marked around its circumference in connection with the positioning marks thereon, with the letters "V," "D," "C," "H," "R," "U," and "L," indicating, respectively, vertical, down, column, horizontal, right, up and left.

As shown in Figures 14 to 25, inclusive, some targets are duplicated in making a complete rotation of the target-forming attachment. This, however, we deem not objectionable because the operator can in this way secure a proper adjustment for a desired target by rotating the target-forming attachment in either direction one half revolution or less.

In Figure 14 it will be seen that in the

formation of a wide vertical ribbon target, the diametrically opposite ports A and B register with diametrically opposite ports 11^a. The port C is closed.

In Figure 15, produced by partial rotation of the target-forming attachment, ports A and B are closed while port C registers with one of the upper ports 11^a to produce a "down target," i. e., one in which the material of the ejected column has been diverted downwardly and forms a unilateral crescentic or semilunar target. This target is advantageously employed in painting floors or other horizontal surfaces.

In Figure 16, all of the ports A, B and C are closed, and hence a circular target will be produced.

In Figure 17, the target forming attachment has been adjusted approximately one quarter of a revolution from its attributed starting point, and ports A and B are now brought into play to produce a wide horizontally disposed ribbonlike target.

In Figure 18, by a slight further adjustment, ports A and B are closed and port C is brought into play so as to produce a unilateral crescentic target to the right of the axial line of the column. This deflection of the target towards the right is advantageously employed in narrow spaces where it is difficult to manipulate the gun.

In Figure 19, all of the ports A, B and C are closed and a circular target will thus be produced.

In Figure 20, the target forming attachment has been adjusted until it has reached a position 180° or one half revolution from its starting point, shown in Figure 14, and in which a wide vertical ribbonlike target is produced.

In Figure 21, ports A and B are closed and port C is open to deflect the column upwardly. This "up" target is advantageously used in painting ceilings and the undersurfaces of large articles of furniture.

Figures 22 and 23 produce column and wide horizontal ribbonlike targets, such as heretofore described with reference to Figures 16 and 17; and in Figure 24 a unilateral left target is produced by bringing port C opposite one of the openings 11^a. This left target is similar to the right hand target produced by the position of the parts shown in Figure 18, but, of course, is deflected in an opposite direction.

In Figure 25 all of the ports A, B and C are closed and in this position of the parts a circular target will be produced. A further adjustment of the target-forming attachment will produce a wide vertical target such as described with relation to Figure 14.

It will be observed that in addition to the adjustments of the target-forming attachment just described, other intermediate positions may be used in the production of other

and differently shaped targets. For instance, instead of relying upon an extra port C whose jet is directed towards the axial line of the column in the production of 5 right, left, down and up targets, all unilateral and crescentic, a port similar to one of the ports A and B might be employed in the production of a peculiarly shaped asymmetric target, one end of which is semicircular 10 in form and one side of which is elongated or provided with a tail, the major axis of the entire target being about one half as long as that of the wide ribbonlike target referred to.

15 In order to hold the target forming attachment to its seat, we preferably arrange a washer 13 against the base ring thereof, and hold said washer and base ring in position by means of the nozzle 9. There is no 20 adjustment of the nozzle 9 in this construction, and hence the valve seat in the base ring can be held firmly to its seat by the fixed position of the nozzle without interfering with the freedom of rotation, in 25 either direction, of the target forming attachment.

In Figures 7 to 13, inclusive, we have shown a modified form of our invention in which the target forming attachment is provided with a greater number of jet or blast ports (five) while the valve ring seat is provided with a fewer number of ports (four). In this construction, 1 is the casting in which are formed the air and paint conduits 30 as before described controlled by suitable valves (not shown). 11^a is the valve ring seat having four ports 11^a preferably equidistantly spaced apart, as shown in Figure 9. 12^b is the target-forming member having 35 port a, b, c, d and e terminating in angularly disposed openings through which are projected jets or blasts of air as indicated by the arrows in Figures 7 and 8. 13^a is a washer bearing against the interior shoulder on the base ring 12^y of the target-forming member, and 14 is a lock nut (corresponding in this function to the nozzle 9 heretofore described) which is threaded on the barrel to hold the washer and target-forming member in position. Instead of 40 mounting the paint controlling valve in the end of the nozzle, as described with respect to the form shown in Figures 1 to 6, inclusive, we adjustably mount said valve by 45 means of the threads on the end of the nipple 7^a, as shown more clearly in Figure 7. The nipple in this form is provided with an annular paint chamber 9^b (in connection with the paint conduit), and the central bore 50 of the nipple communicates with this paint chamber by means of a plurality of diagonally disposed ports 9^c. The paint controlling valve has a central bore or orifice 10^c of uniform diameter throughout the length 55 of its stem, said stem carrying a disk flange

10^d at its outer end by which it may be rotated, and, through the medium of the threaded flange 10^e, in engagement with the nipple, adjusted longitudinally. The valve stem 10^f is provided with a plurality of diagonally disposed openings 10^g, which, when the valve is in its innermost position, register with the diagonal openings 9^c, as shown in Figure 7 (and diagrammatically in Figure 10). In this position of the parts, the greatest quantity of paint can be drawn by a siphoning or suction action into the bore 10^c, by the compressed air passing therethrough; and, of course, where drawn into the bore, will be forced out by the atomizing stream 80 of air in the form of a tapered (conical) column which will, in the absence of disturbing influences, produce an evenly distributed and uniformly applied atomized coating in the form of a round or circular target. A slight rotation of the valve stem will cut off this maximum supply, but we do not rely upon this circumferential movement to accomplish this, preferring to gradually cut off the paint supply by a longitudinal displacement of the valve stem (as shown in 85 Figure 11). By continuing to unscrew the valve, the ports 10^g will finally be moved out of register with the ports 9^c, thus entirely 90 shutting off the supply of paint; and a continued further outward movement of the stem will gradually place the bore of the nipple in direct communication with the ports 9^c, as shown in Figure 12. In this 95 position of the parts, the paint will be forced back through the ports 9^c, the paint duct and into the supply tank, where the air pressure will, in addition to clearing and cleaning out these passages, agitate and mix the paint. To obtain a stronger back pressure, 100 the operator may place his finger over the opening 10^e to close it, when the atomizing pressure can be forced back into the paint tank. The target-forming member may also 105 be adjusted to a "C" (column) position to 110 get a full back pressure.

In Figure 26, we have shown diagrammatically the "W. V." position of the target-forming member in producing a "wide-vertical" target. From the position of the arrows leading from ports a and b it will be seen that the jets or blasts of air strike the column on each side of its center or axial line.

In Figure 27 is shown the "N. H." position, wherein the ports c and d register with the vertically aligned valve-seat ports 11^a and from the direction indicated by the arrows leading from these ports c and d, it will be observed that the jets or blasts of air are directed towards the center of the atomized column; hence a "narrow-horizontal" or elliptically-shaped target will be produced.

In Figure 28, the target-forming member

has been further adjusted in a clockwise direction to its "D" position, wherein port *e* directs a single jet or blast of air downwardly upon and at the center of the column of 5 atomized paint to produce a unilateral or crescentic "down" target. 70

In Figure 29, all of the ports *a*—*b*—*c*—*d* and *e* are closed, hence this "C" position will produce a conical "column" spray forming a round target. 10

In Figure 30, the "W. H." position is indicated, in which the ports *a* and *b* are brought into register with the horizontally aligned ports 11° to produce a "wide-horizontal" or solid ribbonlike target. 15

In Figure 31, the "N. V." position has been reached, in which the ports *c* and *d* are in register with the horizontally aligned targets to produce a "narrow-vertical" target 20 get of elliptical shape.

In Figure 32, the port *e* is brought into register with one of the ports 11° in the "R" position, to produce a "right" or crescentic unilateral target, bulged thusly:).

25 The "C" (column) position shown in Figure 33 produces the same results as shown by the position of the parts in Figure 29 heretofore described: the "W. V." (wide-vertical) position of the parts shown in 30 Figure 34 will produce the same results described with reference to Figure 26; the "N. H." (narrow-horizontal) position of Figure 35, the same as Figure 27; the "U" (up) position of Figure 36 being the reverse 35 concentric of the "D" (down) position of Figure 28; and the "L" position of Figure 37 producing a "left" or unilateral target (the reverse of Figure 32) bulged thusly: (.

In an application filed by Walter A. Heinrich May 10, 1921, Serial No. 468,314, Patent 40 No. 1,438,239, there is disclosed a fan-forming attachment having a crater-like recess in its face, in the side walls of which are provided ports for emitting blasts of air 45 upon opposite sides of the column of ejected material. We utilize this crater-like feature in part in the head ring of our target-forming attachment but in order to promote the circulation of air through the crater, we cut 50 away the inner wall thereof so as to avoid some of the eddies formed when a solid back or inner wall is present.

We claim:

1. The method of applying a coating 55 which consists in ejecting a stream of material and then diverting said stream by directing a jet of gaseous fluid thereagainst and to one side of the axial center thereof.
2. The method of applying a coating which 60 consists in ejecting a column of material and then diverting said column by directing a jet of gaseous fluid thereagainst and at each side of the axial center thereof.
3. The method of applying a coating 65 which consists in ejecting a column of mate-

rial, and then diverting said column by directing a jet of gaseous fluid against one side only thereof and at an angle less than ninety degrees relative to the axial line of said column. 70

4. The method of applying a coating which consists in ejecting a column of material, and then diverting the edges of said column by jets of gaseous fluid which pass each other at a point within the zone of said 75 column.

5. A spray gun having air and paint conduits, a valve seat having a plurality of air ports communicating with the air conduit, a member movable with relation to said valve seat and provided with ports which are designed to be successively registered with ports in the valve seat and to eject streams of air having non-intersecting center lines. 80

6. The combination of a spray-gun having means for delivering a column of material under pressure and against a surface to be coated, thereby producing a circular target, and means for directing a blast of air 90 against one edge only of said column of material to produce a non-circular target. 85

7. The combination of a spray-gun having means for delivering a column of material under pressure and against a surface to be coated, thereby producing a circular target, and adjustable means for diverting said column of material to produce a plurality of targets of unilateral and bilateral shapes, 95 said adjusting means including at least one auxiliary passage adapted to eject a stream of air against said column of material in a direction disaligned with the axial center of said column. 100

8. A target-forming member for spraying 105 apparatus comprising a base ring, parallel spaced arms, and a head ring, having a craterlike face and provided with air blast ports in the sides of the crater.

9. Spray producing means, in combination 110 with a target-forming ring having a craterlike recess through the center of which the spray is ejected, blast ports in the side walls of said crater for producing differential targets, and means for differentially controlling 115 said target-forming blast ports.

10. An air blast nipple for material-spraying-devices, comprising a member provided with an air conduit, and means at the end of said conduit for ejecting a circular 120 series of separate blasts of air.

11. An air blast nipple having a main central orifice for the emission of air under pressure and a series of smaller orifices disposed around said main orifice. 125

12. A material valve formed with an orifice, in combination with an air blast nipple, there being a material supply chamber between the two, and means for shutting off 130 the supply of the material to said orifice.

by adjusting the edges of said orifice against said nipple.

13. A material valve formed with a centrally arranged orifice and diagonally disposed material ports leading to said orifice, a material supply chamber, there being ports leading therefrom and adapted to register with said diagonally disposed material ports, and means for adjusting said valve to control the supply of material through said ports.

14. A material valve formed with a centrally arranged orifice, and lateral material ports, means for supplying compressed air to said orifice, a material supply chamber in communication with said lateral ports,

means for regulating the supply of material to these ports, and means for placing the compressed air supply in direct communication with said material chamber to cause a flow of air pressure therethrough.

15. A nozzle for air brushes comprising a nozzle casing having a central main opening, and side passages having their outlets inclined slightly forwardly relative to the stream from the main bore and tangential to said main bore.

In testimony whereof we hereunto affix our signatures this 9th day of August, 1921.

THEODORE BIRKENMAIER.
